UNITED STATES PATENT OFFICE

152,163

DESIGN FOR A RECORD FILE

George H. Kress, Johnson City, N. Y., assignor to International Business Machines Corporation,
New York, N. Y., a corporation of New York

Application January 31, 1947, Serial No. 136,605

Term of patent 14 years

(Cl. D33—19)

To all whom it may concern:

Be it known that I, George H. Kress, a citizen of the United States of America and resident of Johnson City, Broome County, New York, have invented a new, original, and ornamental Design for a Record File, of which the following is a specification, reference being had to the accompanying drawing, forming part thereof.

Fig. 1 is a perspective view of a record file showing the new design. In this view, the sliding file cover is shown in its open position to reveal the file interior.

Fig. 2 is a perspective view, similar to Fig. 1, showing the sliding file cover in its closed position.

I claim:

The ornamental design for a record file, as shown and described.

GEORGE H. KRESS.
